(57) **CLAIM**

The ornamental design for an intake manifold, as shown and described.

DESCRIPTION

FIG. 1 is a front, right, top perspective view of an intake manifold;

FIG. 2 is a rear, left, bottom perspective view of the intake manifold of FIG. 1;

FIG. 3 is a right side elevation view of the intake manifold of FIG. 1;

FIG. 4 is a left side elevation view of the intake manifold of FIG. 1;

FIG. 5 is a front elevation view of the intake manifold of FIG. 1;

FIG. 6 is a rear elevation view of the intake manifold of FIG. 1;

FIG. 7 is a top plan view of the intake manifold of FIG. 1; and,

FIG. 8 is a bottom plan view of the intake manifold of FIG. 1.

The broken lines show features of the intake manifold that form no part of the claimed design.

1 Claim, 8 Drawing Sheets
